UNITED STATES PATENT OFFICE.

WILLIAM S. INGRAHAM, OF WAUKEGAN, ILLINOIS.

SICKLE-GRINDER.

SPECIFICATION forming part of Letters Patent No. 270,070, dated January 2, 1883.

Application filed November 8, 1882. (No model.)

To all whom it may concern:

Be it known that I, WILLIAM S. INGRAHAM, a citizen of the United States, residing at Waukegan, in the county of Lake and State of Illinois, have invented a new and valuable Improvement in Sickle-Grinders; and I do hereby declare that the following is a full, clear, and exact description of the construction and operation of the same, reference being had to the annexed drawings, making a part of this specification, and to the letters and figures of reference marked thereon.

Figure 1 of the drawings is a representation of this invention in a vertical section. Fig. 2 is a front view of the top part of the machine. Fig. 3 is a detail view of the back of the upper portion. Fig. 4 shows the holder thrown back in a side view.

This invention has relation to devices for grinding the sickles of mowers and harvesting-machines; and it consists in the construction and novel arrangement of a slotted laterally-movable frame pivoted to the front edge of a joint-bar or connecting-piece, which is pivoted at its rear edge to the frame of the grindstone, and the angularly-adjustable flanged holder pivoted to the laterally-movable frame, all as hereinafter set forth.

In the accompanying drawings, the letter A designates the frame of a grindstone, B the stone, and C its shaft, which is preferably mounted on roller-bearings and provided with a crank, D, for connection with a treadle. The frame is provided with short extensions E of its rear arms, designed to support the attachment; or suitable bearings may be provided on a frame of any form in rear of and somewhat above the level of the shaft of the stone for this purpose. In the extensions or supports E are made a number of transverse perforations, *a*, through which is passed the pivot-rod F, whereby the attachment is connected to the frame of the grindstone. Other devices may be used in connecting the attachment; but the pivot-rod is preferred, as it is very simple and strong, and permits the attachment to be readily removed when the grindstone is required for work to which it is not suited.

The attachment is designed to relieve the workman of much of the labor in the manipu-

lation of a heavy sickle on a grindstone, as it sustains the weight of the sickle, and yet permits him to turn it in an oblique position, and to move it endwise and forward and backward with facility. The attachment consists of the holder, the laterally-movable frame, and the connecting-piece, to which the latter is pivoted. The holder H is formed with a flange-bearing, G, and is pivoted centrally near said flange-bearing to the frame K.

The pivot is indicated at L, and is usually extended in front to form a bearing for a lever-cam, M, whereby the sickle, when laid on the flange G, is secured thereto.

The frame K is an upright plate provided with slide-journals b, projecting laterally from its lower portion, and having the arc-shaped slot c in its upper part. The journals b engage bearings d of the connecting-piece P, these bearings being arranged at the front edge thereof, and in such position that the journals b will have sufficient lateral motion therein to permit the adjustment of the holder in bringing the sickle in proper relative position to opposite edges of the grindstone in sharpening opposite edges of a tooth. The connecting-piece P is hinged to the frame of the grindstone by means of the pivot-rod F, which engages bearings e at its rear edge. A stop-bar, S, of the frame A, below said connecting-piece, serves to prevent it from falling too low, so as to come in contact with the grindstone.

The holder H is angularly adjustable on the pivot L, so that it is readily turned from side to side in sharpening the beveled edges of the sickle-teeth, the adjustment to the opposite edges of the stone being easily effected. In order to hold the part H in secure relation to the frame A after adjustment, the holder is provided with a projection or stud, g, in rear, which extends from its upper portion through the arc-slot c, and is threaded to receive a clamp-nut, h.

By means of this attachment a large and heavy sickle can be easily handled on the grindstone. The connecting-piece P is adjustable forward and backward, so that the attachment can be placed more or less forward, according to the depth of the teeth of the sickle and the height of the operator. The connec-

tion can also be vertically adjusted to suit stones of varying diameter or to accommodate the attachment to the wear of a stone.

Having described this invention, what I claim, 5 and desire to secure by Letters Patent, is—

1. The combination, with the frame of a grindstone and the pivoted joint-bar or connecting-piece P, of the laterally-movable frame K and the flanged holder H, pivoted to said frame 10 and angularly adjustable thereon, substantially as specified.
2. The sickle-holding attachment for grindstones, consisting of the joint-bar or connecting-piece P, its pivot-rod, the laterally-movable frame K, hinged to said connecting-piece, the flanged holder H, pivoted to the frame K, and 15 its lever-cam, M, substantially as specified.
3. The combination, with an angularly-ad-

justable holder and laterally-movable frame, to which said holder is pivoted, of a joint-bar 20 or connecting-piece having bearings at its front edge for the slide-journals of said frame, and pivoted at its rear edge to the grindstone-frame, substantially as specified.

4. The combination, with the grindstone-frame A and its stop S, of the pivoted connecting-piece P, the laterally-movable frame K, and angularly-adjustable holder H, substantially as specified.

In testimony that I claim the above I have 30 hereunto subscribed my name in the presence of two witnesses.

WILLIAM SIDNEY INGRAHAM.
